ELECTRIC SWITCH

George J. Meuer, Milwaukee, Wis., assignor to
Cutler-Hammer, Inc., Milwaukee, Wis., a corporation of Delaware

Application October 29, 1948, Serial No. 57,378

7 Claims. (Cl. 200—153)

1

This invention relates to improvements in electric switches and more particularly switches adapted to control alternating currents.

A primary object of the present invention is to improve the details of construction and assembly of the parts of switches of the aforementioned character.

Another object is to provide an improved form of switch base which is common to all of the forms of switches herein contemplated.

Another object is to provide a novel arrangement of switch base in respect of affording a substantially dust-tight enclosure of its interior wherein is carried the stationary contacts, spring biased contactors and actuating elements associated with the latter.

Another object is to provide a switch base with improved construction and arrangement of its wiring terminals, and

Another object is to provide in connection with non-latching and latching trigger type operating superstructures for electric switches, improved arrangement of the same and their operating connections to afford compactness of the switch assemblies so as to facilitate mounting in tool-handle housings or receptacles.

Other objects and advantages of the invention will hereinafter appear.

The switch base, which is common to all the various forms of switches herein contemplated, in certain respects is similar to that disclosed in the Krieger Patent 2,295,688 issued September 15, 1942, and certain forms of operating superstructures herein contemplated are similar in certain respects to forms disclosed in my Patents 1,889,259 issued November 29, 1932; 1,977,078 issued October 16, 1934; and 2,089,032 issued August 3, 1937.

The accompanying drawings illustrate certain embodiments of the invention which will now be described, it being understood that the embodiments illustrated are susceptible of modification in respect of certain structural details thereof without departing from the scope of the appended claims.

In the drawings:

Figure 1 is an elevational view of a switch (twice normal scale) showing the bottom side of a molded insulating base, which is common to all of the various switches herein disclosed—the contact wiring terminals and an auxiliary wiring lug being shown in position, together with one preferred form of trigger type switch operating mechanism which is shown in section.

Fig. 2 is a sectional view, on the line 2—2 of

2

Fig. 1 with the trigger mechanism being shown in elevation.

Fig. 3 is a sectional view, on the line 3—3 of Fig. 1 showing the switch contacts and wiring terminals.

Fig. 3a is a fragmentary view of the lower right hand corner portion of the bottom side of the switch base shown in Fig. 1 but with the terminal member, wiring lug and securing rivets removed.

Fig. 4 is a view of the upper surface of the switch base shown in Fig. 1 with the trigger lever and associated operating mechanism cut away.

Fig. 5 is a sectional view, on the line 5—5 of Fig. 2.

Fig. 6 is a fragmentary sectional view of one corner of the switch base to further illustrate the wiring terminal associated with certain of the switch contacts.

Fig. 7 is a view similar to Fig. 1 showing a modified form of switch, wherein the trigger operating mechanism is provided with a latch and wherein the wiring lug is omitted.

Fig. 8 is a fragmentary view of the switch shown in Fig. 7, viewed at right angles thereto, and with portions of the operating mechanism and mounting means therefor being shown in section.

Fig. 9 is a view in longitudinal section of another modified form of the switch wherein a toggle lever type of operating mechanism is provided together with a three-hole type mounting bracket, and Fig. 10 is a fragmentary view partially in section to illustrate another modified form of switch wherein a toggle lever operating mechanism is provided together with a one-hole mounting bracket.

Referring to the switch shown in Figs. 1 to 6, generally considered it comprises a switch base in which are carried stationary and movable contacts and an operating superstructure of the trigger type. The arrangement of the stationary and movable contacts in the switch base is similar to that disclosed in the aforementioned

Krieger patent although differing therefrom in respect of certain details. As will now be described the switch base of the instant form of switch differs from that disclosed in the Krieger patent in respect of its wiring terminals and the means utilized to enclose the upper surface of the switch base.

More particularly considered the numeral 15 designates a preferred form of molded insulating base formed of any suitable insulating material such as a melamine resin. Opening to the upper

surface 15^a of base 15 are three longitudinally parallel recesses 16, 17, 18 as best shown in Fig. 4. The opposite side recesses 16 and 18 are suitably formed, as best shown in Fig. 3, to accommodate respectively pairs of stationary contact members 19, 19 and cooperating spring biased substantially U-shaped bridging contactors 20, 20 which underlie respective pairs of the contact members 19, 19. On their bottom surfaces contact members 19 are provided with contact tips 19^a which are preferably formed of silver or a silver base material and which are suitably secured to members 19 as by spot welding. Movable contactors 20, 20 are provided on the upper surfaces of their outwardly extending arms with contact tips 20^a which are adapted to engage with the stationary contact tips 19^a. Each of the movable contactors 20 has bearing against its intermediate portion one end of a coil compression spring 21 which spring bears at its opposite end against the bottom of the respective recess 16 or 18 as best shown in Fig. 3. Contact members 19 are secured within recesses 16 and 18 by rivets 22 which extend through suitable openings formed in base 15 to the bottom side of said base.

A flat punched insulating plate 23 is accommodated edgewise and transversely of recesses 16, 17 and 18 in alined notches 24 and 25 which respectively interconnect recesses 16—17 and recesses 17—18. Also end portions of plate 23 are accommodated within the U-shaped intermediate portions of contactors 20 to bear upon said contactors as best shown in Figs. 3 and 4.

Overlying the upper edge of plate 23 and located in base recess 17 is a cam operating member 26. Cam 26 comprises a strip having a flat portion 26^a which overlies the upper edge of plate 23 and which at one end is of T-shape, as best shown in Fig. 4. The T-shape end of portion 26^a is located within a corresponding T-shape portion 17^a of recess 17 opening to the upper surface 15^a of base 15. The bottom wall of recess 17^a slopes upwardly from a shoulder of recess 17 at a slight angle toward the upper surface 15^a of the base, as best shown in Fig. 2. The cam 26 has a portion 26^b which projects upwardly from the free end of portion 26^a at a right angle therefrom and which extends through a small rectangular opening formed in a flexible rubber or rubber like diaphragm 27 of sheet form that overlies the upper surface 15^a of the base. Further the cam 26 has at the upper end of portion 26^b and exposed above the diaphragm 27 a portion 26^c which bears substantially at a right angle to portion 26^b and which is in a substantially parallel and overlying relation to the portion 26^a. Additionally cam 26 has a portion 26^d extending from the portion 26^c at an obtuse angle toward the portion 26^a, said portion 26^d having a free end. Adjacent its free end the portion 26^d is concavely curved in its longitudinal dimension.

Diaphragm 27 overlying upper surface 15^a of the base affords a substantially dust-tight enclosure for recesses 16, 17, 18 and 17^a and for the notches 24 and 25. It also affords retention of the T-shape end of cam 26 within recess 17^a wherein said cam is afforded pivotal bearing support.

As will be apparent when cam 26 is pivotally moved inwardly of base 15 it causes plate 23 to move downwardly in said base against the bias of springs 21, 21 bearing upon contactors 20, 20, thereby effecting disengagement of the contact tips 20^a of the contactors from contact tips 19^a of the stationary contact members 19 for circuit

interruption. When the cam 26 is relieved of downward pressure the springs 21 act on the contactors to reengage them with the stationary contact members and to return said cam to its outer extreme position.

Whereas in the aforementioned Krieger patent a molded insulating cam member is utilized I find that the cam 26, formed as by the stamping and punching of a strip of sheet metal, is particularly useful in conjunction with the diaphragm 27.

Base 15 on its outer face paralleling the afore-described recessed face is provided with a longitudinally extending, substantially rectangular central rib 15^b as best shown in Figs. 1 and 2. Intersecting the rib 15^b at a point midway between its opposite ends and lying on opposite sides thereof are ribs 15^c, 15^c, whose form is best shown in Figs. 1, 3 and 5. The ribs 15^b and 15^c separate, and act as barriers between, the four corner portions 28, 29, 30 and 31 of the surface of the base from which said ribs project.

The base surface portions 28, 29, 30 and 31 are alike in form. By way of example, as best shown in Figs. 1, 3 and 6, the portion 28 has surfaces 28^a and 28^c lying in different parallel planes and a sloping interconnecting surface 28^b which as shown does not meet the surface 28^c exactly but is slightly offset therefrom, the intermediate surface being perpendicular to surface 28^c. As best shown in Figs. 3 and 3^a, surface 28^b has formed therein an opening which gives access to a recess 28^c in the base, said recess having parallel side walls and intermediate walls meeting to give the recess a triangular form. Also, as best shown in Figs. 3, 3^a and 6, the surface 28^c has a small rectangular opening therein giving access to a recess 28^f extending inwardly of said base for a short distance, the recess to receive with a snug fit a rectangular part. Each of the other recesses 29, 30 and 31 have surfaces and recesses like those aforementioned in connection with portion 28 and in each instance such surfaces and recesses are designated by identical subscripts.

As best shown in Figs. 1, 3 and 6, like terminal members 32 are mounted on portions 28, 29, 30 and 31 of the base. Each terminal member 32 is provided with a reduced rectangular end extension 32^a to project into one of recesses 28^f, 29^f, 30^f, 31^f, such extension being an integral part of a portion 32^b carrying a binding screw 39, the shank of which extends into one of the recesses 28^a, 29^a, 30^a, 31^a. Portions 32^c of said terminal members 32 are perforated to accommodate the shanks of the rivets 22 which in addition to their function aforementioned afford rigid securing of members 32 to base 15 and electrical connection of each terminal member with a stationary contact member 19.

As will be noted the arrangement of terminal members 32 is substantially different from that disclosed in the aforementioned Krieger patent. The instant arrangement facilitates the making of wire circuit connections with the switch and prevents disturbing the alinement and positioning of the stationary contact members 19 within the switch base. Any strains occurring in the making of wire connections are localized to the terminal members 32. It will also be noted by those skilled in the art that the arrangement of terminal members 32 provides access for making the equivalent of bottom and/or end wiring connections therewith.

An auxiliary wiring lug 33 is secured to the base 15 centrally with respect to the four terminal

members 32 as best shown in Figs. 1, 2 and 5. Lug 33, which is preferably formed by stamping and punching of a strip of brass, is provided with a flat, elongated oval shape portion 33^a which engages with the rib 15^a of base 15 between the ribs 15^c, 15^e thereof. Lug 33 is also provided with small rectangular extensions 33^b, 33^c which project at a right angle to the portion 33^a on opposite edges of the latter. A circular opening is provided in the portion 33^a midway between its ends to accommodate a short cylindrical boss 15^f of base 15 which extends outwardly between the ribs 15^c, 15^e.

Two other circular openings of smaller diameter are formed in the portion 33^a on opposite sides of the aforementioned opening. A hollow rivet 34 penetrates lug 33 through one of the last mentioned openings, said rivet being contained in a recess 15^g of base 15 and extending outwardly from said base. Recess 15^g in the instant form of switch is broached through to communicate with the recess 17, the bottom wall of which is of slightly greater width than that of recess 15^g. Rivet 34 is provided with a rectangularly shaped head snugly fitting recess 17 and with a shank extending through recess 15^g and lug 33 to have its end upset over the outer surface of lug 33 to thereby secure the latter to base 15. Rivet 34 is suitably threaded internally to receive a binding screw 35. The other of said openings in lug 33 is suitably threaded to receive a binding screw 36 which extends inwardly of base 15 within a clearance recess 15^h formed in the latter. A thin fiber insulating member 37 having a shape like that of the portion 33^a of lug 33, but at all points extending a substantial distance therebeyond, is interposed between lug 33 and base 15.

As will be understood the lug 33 and the parts associated therewith have no electrical connection with the terminal members 32 or stationary contact members 19 and is provided as an auxiliary "bussing lug" or wiring bracket for convenience in anchoring wires to the switch. Lug 33 and the parts associated therewith may be omitted if desired as shown in connection with the modified forms of switches hereinafter to be described.

A combined cover and frame member 38, preferably formed by punching and stamping a sheet metal plate has a portion 38^a which in part overlies the surface 15^a of base 15 and portions 38^b and 38^c which extend beyond said base. As viewed in Fig. 5, the portion 38^a of said member is of substantially inverted channel shape in vertical cross section. As best shown in Fig. 2, the portion 38^a has a pair of openings 39 and 40 extending therethrough and formed for countersinking of the upset ends of rivets 41 which provide for securing of member 38 to base 15. Openings 39 and 40 register respectively with openings 42 and 43 extending through base 15 and being enlarged adjacent the surface of the base to provide inset annular shoulders for abutment by the heads of the rivets 41.

A stiff fiber insulating plate 44 coextensive with the surface 15^a of base 15 and diaphragm 27 and having a rectangular central opening 44^a is positioned between the portion 38^a of member 38 and a flexible fiber member 45, overlying diaphragm 27. Members 44 and 45 have openings to accommodate the shanks of rivets 41.

Although not shown in the drawings, the member 45 in practice would commonly extend beyond the outer side walls of base 15 as viewed in Fig. 1 to be bent to form an insulating envelope around

the bottom of base 15 to protect against grounding of wires connected to the terminal members 32 and the lug 33.

As best shown in Figs. 1 and 2, the member 38 at the end of portion 38^a turns inwardly providing a portion 38^b paralleling the end of base 15 and at the end of portion 38^b turns to provide a portion 38^c lying in a plane paralleling that of portion 38^a. Extending from the portion 38^c is a half-moon shaped lug 38^d which depends at an angle to the plane of portion 38^c. The portion 38^c merges with a portion 38^e which is slightly offset therefrom and also with a portion 38^f which is offset therefrom to a greater degree. A lug 38^g sheared from the portion 38^c projects at a right angle thereto and provides support for a coiled spring 46.

A contactor actuating member 47, preferably formed from a sheet metal plate by punching and stamping, has a portion 47^a reciprocably mounted in the channel section of portion 38^a as best shown in Figs. 1, 2 and 5, said portion 47^a having a slot 47^b freeing it for reciprocation without interference by the penetrating connection comprising right hand rivet 41. Portion 47^a has at its free end a rectangular extension 47^c to bear upon and to be moved along the portions 26^c and 26^d of cam 26, said extension being outwardly turned and projecting into a channel provided in part 38^a of member 38. Portion 47^a of member 47 is connected with a portion 47^d which bears at a right angle thereto and which lies in a parallel relation with the portion 38^b of member 38. Portion 47^d in turn is connected with a portion 47^e which bears at a right angle therefrom in a parallel relation to the portion 47^a, and which along a greater portion of its length is of reduced width. Adjacent its free end the portion 47^e is provided with a circular opening through which extends a reduced portion of a tubular bushing 48. Bushing 48 is rigidly secured to portion 47^e by upsetting of the end of said reduced portion of said bushing which extends beyond said portion 47^e.

For actuation of member 47 there is provided a trigger type actuator 49 which is similar in form to certain trigger actuators disclosed in my Patents 1,889,259, 1,977,078 and 2,089,032. However, as will now be described the instant trigger actuator differs in respect of certain details of construction, its operating connections and the way in which it is mounted with respect to the switch base.

Actuator 49 generally considered is of saddle-shape. More particularly it is U-shaped in transverse vertical cross section and comprises parallel depending side portions 49^a and 49^b interconnected by a portion 49^c which is concavely curved in its longitudinal dimension to afford good "finger grip." Actuator 49 is mounted in a straddling relation to the portions 38^c, 38^d, 38^e and 38^f of member 38 and is afforded pivotal support by a pivot pin 50 which extends through aligned openings formed in the side portions 49^a and 49^b of said actuator and through a hollow bushing 51 penetrating the portion 38^e and being secured thereto in the manner aforeindicated for the bushing 48. Pin 50 is provided at one end with an enlarged head which bears against the outer surface of portion 49^a and at its opposite end is upset over the outer surface of the portion 49^b thereby being secured against axial movement. The portion 49^c is depressed at a point between the portions 49^a and 49^b to form an abutment for spring 46. Portions 49^a and 49^b are provided with 75 additional aligned openings for a cylindrical pin

52 which extends through the bushing 48 and which is secured to the actuator in the manner aforesaid for the pin 50. The shank diameter of pin 52 is substantially less than the inner diameter of bushing 48.

As will be understood spring 46 biases actuator 49 for pivotal movement in the clockwise direction as viewed in Fig. 1, but such movement being limited by engagement of the shank of pin 52 with the marginal side of portion 38^c of member 38.

As shown in Fig. 1, two circular openings 53 and 54 are provided in portion 38^c of member 38 to provide for attachment of the switch assembly within a tool handle or other housing as by bolts or screws which are accommodated by said openings.

As the switch stands in Figs. 1 and 2, the member 47 is moved to its extreme left position due to the bias of spring 46 which acts thereon through actuator 49, pin 52 and bushing 48. As aforesaid when member 47 is in such position, its portion 47^c engages with the portion 26^c of cam 26 and thereby effects disengagement of the contactors 20 from the stationary contact members 19. As will be appreciated, in its extended relation shown in Fig. 1 spring 46 must be strong enough to overpower the springs 21, 21 in the switch base to collapse the same.

When the actuator 49 is pivotally moved against the bias of spring 46 in the counter-clockwise direction as viewed in Fig. 1, the pin 52 is caused first to take up the play thereof within the bushing 48 and then to engage the opposite wall of bushing 48 and move member 47 to the right. When member 47 is moved sufficiently far to the right its portion 47^c moves out of engagement with the portion 26^c of cam 26 and onto the portion 26^d of the latter. Then the bias of springs 21, 21 acting through contactors 20, 20, member 23 and cam 26 cause member 47 to move to the right with more or less snap action. As a result the contactors 20, 20 engage with the stationary contact members 19 and the bushing 48 moves free of the shank of pin 52 until it again re-engages with the same on the opposite side. The subsequent re-engagement of bushing 48 with pin 52 provides an audible signal and a tactily perceptible signal which is transmitted through pin 52 and actuator 49 to indicate that the switch has been operated to its circuit completing condition. Actuator 49 may only be moved against the bias of spring 46 to a limited extent and is moved to such limit when the bottom surface of its portion 49^c engages with the lug 38^d of member 38. Releasing the actuator 49 for movement under the bias of spring 46 effects return of the switch to its circuit interrupting condition aforesaid.

The modified form of switch illustrated in Figs. 7 and 8 is identical in respect of the switch base 15, the contact mechanism carried within said base, the cam operating member 26, diaphragm 27, insulating plate 44, flexible insulating member 45 and the wiring terminals 32 shown and described in connection with the switch illustrated in Figs. 1 to 6, with the exception that the wiring lug 33 and its associated binding screws 35 and 36, rivet 34 and fiber insulating plate 31 are omitted from base 15 and the recess 15^e is not broached through to the recess 17 in base 15 as aforesaid. As will now be described the modified form of switch dif-

fers principally in respect of its trigger actuator which is of the latching type.

As shown in Figs. 7 and 8, the switch is provided with a combined cover and frame member 56 having a portion 56^a which overlies the insulating plate 45. Portion 56^a is essentially of the same channel-shape cross sectional form as the portion 38^a of member 38 aforesaid and is provided with a pair of spaced openings 57 and 58 which register with corresponding openings formed in diaphragm 27, plate 44, member 45 and openings 42 and 43 in base 15. Somewhat elongated depressions are formed about the openings 57 and 58 in portion 56^a to accommodate the upset ends of the rivets 41 which secure member 56, plate 44, member 45 and diaphragm 27 in assembled relation to the surface 15^a of base 15.

Member 56 is provided with portions 56^b and 56^c which are integrally formed with the portion 56^a and which extend to the left and right beyond the base 15 respectively. Portion 56^c is connected with portions 56^d which is offset therefrom as shown in Fig. 8. A lug 56^e extends from the portion 56^c at a right angle thereto to provide an abutment for spring 59. Portion 56^d has fixed thereto as by riveting a perpendicularly disposed post 61 projecting in the same direction as spring abutment lug 56^e.

30 An operating member 62 is provided with a portion 62^a slideable within the channel section of portion 56^a of member 56. A portion 62^b, similar in form to the portion 48^c of member 48 aforesaid, is integrally connected with the portion 62^a and like said portion 48^c is adapted to engage with the portions 26^c and 26^d of cam 26.

Also member 62 is provided with a portion 62^c which extends from the portion 62^a with offset therefrom as shown in Fig. 8; the contour of portion 62^c being best shown in Fig. 7. Portions 62^a and 62^b have a slot 63 therein to afford it for reciprocation clearance from the parts to pass through openings 64 and 65 in member 56^c as well as from the parts discussed in connection with the first form of switch. Also portion 56^d is for a like purpose provided with a slot 66 to afford clearance in respect of the aforementioned post 61.

50 A trigger type actuator 68 is provided to effect rectilinear movement of member 62, said actuator being pivotally supported on part 56 as later described. Actuator 68 is substantially U-shape in transverse vertical cross section and comprises parallel depending side portions 68^a and 68^b and a connecting portion 68^c. The portion 68^c, like the portion 50^c of the trigger actuator aforesaid, is concaved in longitudinal dimension to provide for good "finger grip." Portion 68^c is depressed at a point thereon to provide a boss between the portions 68^a and 68^b to afford retention of the upper end of the spring 59.

55 Portion 68^a has an extended portion 68^e which is in a coplanar relation therewith and as best shown in Fig. 7 portion 68^e has an open notch 69 formed therein. The notch 69 receives post 61 of part 56^d with sufficient clearance to permit desired movement of part 68^e. Also notch 69 receives a post 67 fixed to part 62^c of reciprocating member 62, the part 68^e by virtue of the slot having extensions 68^f and 68^g to be engaged alternatively with said post 67 subject to appreciable lost motion.

The portion 68^b of the actuator has a portion 75 68^h (Fig. 7) which bears at a right angle toward

the portion 68^a, and portion 68^b together with portion 68^c supports a reciprocable latch 70. The latch 70 comprises a push button 70^a extending through an opening in portion 68^c, said push button having a portion 70^b of reduced diameter extending through an opening in portion 68^b. A metal washer 71 is secured to the free end of the reduced portion 70^b on the outer side of portion 68^b, as by upsetting of the end of the portion 70^a. The washer 71 limits upward movement of the latch which is biased to such limit by a coil compression spring 72 disposed about the part 70^b to bear at one end against the portion 68^b and at its opposite end against the shoulder formed at the junction of portions 70^a and 70^b.

A pair of aligned openings extending through the portions 68^a and 68^b are provided to accommodate the shank of a pivot pin 73 which is rigidly secured to the portion 56^d of member 56. The pin 73 is provided with a reduced end portion projecting through an opening in portion 56^d and the part of said end portion extending beyond portion 56^d is upset to rivet the pin to said portion. A washer like spacer 74 is disposed about the shank of pin 73 between the portion 56^d of member 56 and the adjacent surface of the portion 68^a of actuator 68. The portion of pin 73 which extends beyond the outer surface of the portion 68^b of actuator 68 is peripherally grooved to accommodate a horse shoe shaped snap-on washer 75 of a well-known type. The washer 75 when snapped in place on pin 73 overlying the outer surface of portion 68^b prevents movement of actuator 68 axially of pin 73. The aforescribed aligned openings in portions 68^a and 68^b are of slightly larger diameter than the diameter of the shank of pin 73 so as to afford free pivotal movement of actuator 68 about said pin.

As aforescribed, the portion 56^c of member 56 has formed therein the circular openings 64 and 65 to accommodate screws or bolts for securing the switch unit within a tool handle or housing. The portion 56^b is provided with two openings 76 and 77 which are located therein in relatively similar positions to the location of openings 64 and 65 in portion 56^c. Portions 56^b and 56^c are respectively thickened for a certain distance about their openings 64 and 76 and said openings are threaded.

As the switch stands in Figs. 7 and 8 it is in its normal circuit interrupting condition; spring 59 being of sufficient strength to overpower the springs associated with the movable contactors in the base 15.

When the trigger actuator 68 is pivotally moved against the bias of spring 59 in the counterclockwise direction as viewed in Fig. 7, it moves without effect until its extension 68^c engages with the post 67. Further pivotal movement of the actuator then causes the member 62 to slide to the right as viewed in Figs. 7 and 8. When member 62 is moved sufficiently far to the right its portion 62^b moves out of engagement with the portion 26^c of cam 26 onto the portion 26^d of the latter. Thereafter member 62 is caused to be moved farther to the right with more or less snap action by the bias of the springs of the movable contactors in the switch base 15 as aforescribed in connection with the form of switch illustrated in Figs. 1 to 6. Accordingly circuit completing condition is effected within the base 15. The snap movement of member 62 to the right causes the post 67 to move

75

out of engagement with the extension 68^c and to re-engage extension 68^c of actuator 68. The re-engagement of post 67 with extension 68^c provides an audible signal and also a tactfully perceptible signal which is transmitted through actuator 68 to afford an indication that the switch has been operated to circuit completing condition.

If actuator 68 is pivotally moved in the counterclockwise direction to a certain point farther than is necessary to effect circuit completing condition of the switch, and the latch 70 is depressed to its limit against the bias of spring 72 and held there while actuator 68 is released, the shank 70^b of said latch and the washer 71 will engage and bind against the post 61 effectively latching actuator 68 in a depressed position thereby insuring that the switch will be maintained in its circuit completing condition. In order to release the latch 70, it is merely necessary to slightly depress actuator 68 pivotally in the counterclockwise direction and latch 70 will then be released to move upwardly out of engagement with post 61 under the bias of spring 72.

If actuator 68 is released for free pivotal movement in the clockwise direction under the bias of spring 59 the switch will accordingly be returned to its normal circuit interrupting condition shown in Figs. 7 and 8.

As will be noted the trigger actuators and associated operating connections aforescribed for the switch assemblies shown in Figs. 1 to 6 and Figs. 7 and 8 respectively are so arranged and mounted with respect to the switch bases 15 that they are confined between boundaries comprising the outer surfaces of members 38 and 56, as the case may be, and the outer surface of the rib 15^b of the switch bases. Such arrangements afford compact switch assemblies which may be accommodated within a wide variety of tool handle housings or receptacles.

The switch illustrated in Fig. 9 is identical with that of Figs. 1 to 6 in respect of the insulating plate 44 and all of the parts positioned therebelow with the exception that the wiring lug 33, screws 35 and 36, rivet 34, and insulating member 45 are omitted and the recess 15^c is not broached through to the recess 17 in base 15 as aforescribed. The switch assembly of Fig. 9 differs in respect of its operating superstructure which is a preferred form of three-hole mounting, toggle lever type superstructure.

The superstructure of the switch of Fig. 9 comprises a one-piece stamped sheet metal cover plate 78 having a centrally located bulge portion in which is secured a hollow metal bushing 79. A toggle actuator 80 is pivotally supported within bushing 79 on a pin 81 and has an end portion adapted to slidably engage with the portions 26^c and 26^d of cam 26. A conventional form of three-hole mounting bracket 82 is positioned over cover plate 78 and is provided with a suitable central opening to accommodate the bulged portion of cover plate 78 and is also provided with suitable threaded openings adjacent end extremities thereof to afford securement of the switch assembly in suitable housings or receptacles. Plates 82 and 78 are secured together with an insulating plate 83 and diaphragm 27 in assembled relation to the upper surface 15^a of base 15 by screws 84, 84 which are riveted over the upper surface of plate 78.

As will be understood pivotal movement of the lever 80 to the right as viewed in Fig. 9

will effect circuit interrupting condition of the switch, the same being in circuit completing condition as it stands in Fig. 9.

The modified form of switch shown in Fig. 10 is identical with that of Fig. 9 in respect of the cover plate 18 and all parts positioned therebelow. The switch of Fig. 10 differs in respect of having a one-hole mounting, toggle lever operating superstructure somewhat similar to a form of operating superstructure disclosed in the Krieger patent.

The operating superstructure of the switch of Fig. 10 comprises the cover plate 18 aforementioned having a centrally located bulged portion in which is secured an externally threaded, hollow cylindrical bushing 85. A toggle lever actuator 86 is pivotally supported within bushing 85 on a pin 87 and an enlarged hemispherical end portion thereof is adapted to slidably engage with the portions 26^c and 26^d of cam 26 when actuator 86 is pivotally moved about the pin 87. Plate 78, insulating plate 83 and diaphragm 27 are secured in assembled relation to the upper surface of base 15 by the rivets 88, 89 which are only partially shown in the drawing.

As will be understood the switch is operable in the same manner as aforescribed for the switch shown in Fig. 9.

What I claim to be new and desire to secure by Letters Patent is:

1. In combination, a molded insulating base having formed therein a main recess and an auxiliary T-shaped recess of relatively shallow depth jointly opening to one surface of said base and said recesses being otherwise closed, said first mentioned recess communicating with said T-shaped recess, a flexible elastic sheet overlying the upper surface of said base to afford a substantially dust-tight closure for said recesses, said sheet having a relatively small opening formed therein, a one-piece punched and stamped sheet metal cam member having a flat T-shaped portion positioned within said T-shaped recess for pivotal support thereby, a second portion extending from said T-shaped portion and projecting outwardly with a snug fit through the opening in said sheet, a third portion extending from the outer end of said second portion in overlying relationship to said portion first mentioned, and a fourth portion extending from said third portion toward said portion first mentioned, stationary and movable contacts positioned within said first mentioned recess, means for normally biasing said movable contacts into a given relationship to the stationary contacts, an insulating member continuously engaged by the movable contacts and continuously engaged with the first mentioned portion of said cam member, a cover plate overlying said sheet and said insulating base, and fastening means securing said cover plate, said sheet and said base in assembled relation.

2. In combination, a molded insulating base having formed therein a main recess and an auxiliary T-shaped recess of relatively shallow depth jointly opening to one surface of said base and said recesses being otherwise closed, said first mentioned recess communicating with said T-shaped recess, a flexible elastic sheet overlying the upper surface of said base to afford a substantially dust-tight closure for said recesses, said sheet having a relatively small opening formed therein, a one-piece punched and stamped sheet metal cam member having a flat T-shaped por-

70
75

tion positioned within said T-shaped recess for pivotal support thereby, a second portion extending from said T-shaped portion and projecting outwardly with a snug fit through the opening in said sheet, a third portion extending from the outer end of said second portion in overlying relationship to said portion first mentioned, and a fourth portion extending from said third portion toward said portion first mentioned, a plurality of sets of stationary and movable contacts, said movable contacts being normally biased into engagement with said stationary contacts, a movable contact operator underlying said first mentioned portion of said cam member and through the action of said movable contacts normally biasing said cam member to an upper extreme position to permit engagement of said movable contacts with said stationary contacts, a flat insulating plate overlying said elastic sheet and having a relatively large central opening formed therein, a cover and support member overlying said insulating plate, fastening means to secure said sheet, said insulating plate and said base in assembled relation, and movable means having sliding engagement with said third and fourth portions of said cam member, said movable means when moved into engagement with said third portion of said cam member effecting movement of the same inwardly of said base to a lower extreme position to effect disengagement of said stationary and movable contacts, and said movable means when moved into engagement with said fourth portion of said cam affording release of the same for movement to its upper extreme position.

3. In an alternating current controlling switch of the relatively slow-make, slow-break type, in combination, a molded insulating base having a recess opening to one surface thereof only, a plurality of sets of stationary contacts located within said recess, a corresponding number of bridging contactors located within said recess and normally biased into engagement with the respective sets of contacts, a flat plate of insulating material overlying the intermediate portions of the respective contactors and continuously engaged by the latter, a punched and stamped sheet metal cam member pivotally supported within said recess and continuously engaged by said insulating plate, an elastic rubber-like diaphragm secured to said surface of the base and overlying said recess to render the same substantially dust-tight, said sheet having a relatively small opening formed therein to accommodate with a close fit a portion of said cam member extending outwardly therethrough, the exposed portion of said cam member having a plurality of adjacent cam surfaces formed thereon, manually operable actuating means cooperating with one of said cam surfaces to permit movement of said contactors under their bias to their normally engaged position, and said actuating means cooperating with both of said cam surfaces to effect movement of said contactors to and retention thereof in their disengaged position.

4. As an article of manufacture for use with electric switches having a cam operating member, a switch operating superstructure comprising a one-piece sheet metal member having a portion in which is formed a rectangular substantially flat bearing surface which is substantially longer than it is wide, said member being adapted for mounting on the switch housing to form one side thereof, and another portion extending in the same direction a substantial dis-

tance from one end of said first mentioned portion, a one-piece sheet metal switch operating lever having a flat portion which has sliding engagement with said flat bearing surface and a second portion extending a substantial distance therefrom in a parallel relation to said other portion of said member first mentioned, the first portion of said operating lever being adapted for operable engagement with said cam operating member, a trigger type actuator pivotally supported on said other portion of said member first mentioned, means affording a lost motion driving connection between said actuator and said second portion of said lever, and spring means biasing said actuator to one extreme position at which said lever attains a given extreme position relative to said member first mentioned, said actuator being movable against the bias of said spring means and when so moved initially moving a predetermined distance relative to said lever with lost motion, and said actuator thereafter during movement to its other extreme position effecting movement of said lever to its other extreme position relative to said member first mentioned.

5. As an article of manufacture, an electric switch operating superstructure for switches having a cam operating member comprising a one-piece sheet metal cover member having a portion of substantially inverted channel-shape and another portion extending a substantial distance from one end of said channel portion, a one-piece sheet metal switch operating lever having a substantially flat portion located within and having sliding engagement with said channel portion of said member and a second portion extending a substantial distance therefrom in a parallel relation to said other portion of said member, said first portion of said operating lever being adapted for operable engagement with said cam operating member, a trigger type actuator pivotally supported on said other portion of said member in such a manner that its pivotal axis is at a right angle to the plane of said flat portion of said lever, means affording a lost motion driving connection between said actuator and said other portion of said lever, whereby when said actuator is moved initially it moves a predetermined distance relative to said lever with lost motion and thereafter during continued movement of said lever said cam operating member may move independently of said actuator.

6. As an article of manufacture, an electric switch operating superstructure comprising a one-piece sheet metal cover and support member having a substantially inverted channel-shaped portion and another portion extending a substantial distance therefrom in an offset parallel relation, a one-piece switch operating lever having a substantially flat portion located within and having sliding engagement with said channel portion of said member and a second portion extending

therefrom in an offset relation thereto, said second portion of said lever being positioned in an overlapping relation to said other portion of said member, a trigger type actuator pivotally supported on said other portion of said member in such a manner that its pivotal axis is at a right angle to the plane of said flat portion of said lever, means affording a lost motion driving connection between said actuator and said other portion of said lever, and spring means biasing said actuator to one extreme position at which said lever attains a given extreme position relative to said member, said actuator being movable against the bias of said spring means and when so moved initially moving a predetermined distance relative to said lever with lost motion, thereafter during movement to its opposite extreme position effecting movement of said lever to its other extreme position relative to said member.

20 7. In an alternating current controlling switch of the relatively slow-make, slow-break type, in combination, an insulating base, a plurality of sets of stationary contacts positioned on said base, a corresponding number of bridging contactors normally biased into engagement with the respective sets of contacts, a member of insulating material overlying portions of the respective contactors, a cam member pivotally supported upon said base and continuously engaged by said insulating member, an elastic rubber-like diaphragm secured to said base and overlying said base to render the same substantially dust-tight, said sheet having a relatively small opening formed therein to accommodate with a close fit a portion of said cam member extending outwardly therethrough, the exposed portion of said cam member having cam surfaces formed thereon, manually operable actuating means cooperating with said cam to permit movement of said contactors under their bias to their normally engaged position and to effect movement of said contactors to and retention thereof in their disengaged position.

GEORGE J. MEUER.
